Primary Examiner — Calvin E Vansant(57) **CLAIM**

The ornamental design for a grow box, as shown and described.

DESCRIPTION

FIG. 1 is a front elevational view of a first embodiment of a grow box showing my new design;
 FIG. 2 is a rear elevational view of FIG. 1;
 FIG. 3 is a left side view of FIG. 1;
 FIG. 4 is a right side view of FIG. 1;
 FIG. 5 is a top plan view of FIG. 1;
 FIG. 6 is a bottom plan view of FIG. 1;
 FIG. 7 is a top, front and right side perspective view of FIG. 1;
 FIG. 8 is a bottom, rear and left side perspective view of FIG. 1;
 FIG. 9 is a front elevational view of a second embodiment of the grow box;
 FIG. 10 is a rear elevational view of FIG. 9;
 FIG. 11 is a left side view of FIG. 9;
 FIG. 12 is a right side view of FIG. 9;
 FIG. 13 is a top plan view of FIG. 9;
 FIG. 14 is a bottom plan view of FIG. 9;
 FIG. 15 is a top, front and left side perspective view of FIG. 9; and,
 FIG. 16 is a bottom, rear and right side perspective view of FIG. 9.
